UNITED STATES PATENT OFFICE

2,672,981

PACKAGE OF STACKED RECEPACLES

Carl T. Colgren, Kalamazoo, Mich., assignor to
Sutherland Paper Company, Kalamazoo, Mich.

Application September 8, 1947, Serial No. 772,665

9 Claims. (Cl. 206—65)

1

This invention relates to improvements in a package of stacked receptacles.

The main objects of this invention are:

First, to provide a package of stacked receptacles such as drinking cups in which the receptacles are fully protected by an enclosing wrapper which retains them in their stacked condition, the receptacles being fully protected, the package being such that one package of stacked cups may be nested with other similar packages.

Second, to provide a package of stacked receptacles wrapped in a heat sealable transparent wrapper and having a label associated therewith, the label being within and visible through the wrapper and supported in position by the wrapper.

Third, to provide a receptacle package of the character described in which the top receptacle of the stack is fully covered or protected by the wrapper.

Fourth, to provide a receptacle package having these advantages which may be very economically produced and one which is highly attractive in appearance.

Further objects relating to details and economies of the invention will appear from the description to follow. The invention is defined in the claims.

Fig. 1 is a top perspective view of a package of drinking cups embodying my invention.

Fig. 2 is an enlarged fragmentary view, mainly in vertical section on line 2—2 of Fig. 3.

Fig. 3 is a bottom plan view.

Fig. 4 is an enlarged fragmentary view on a line corresponding to line 4—4 of Fig. 2.

Fig. 5 is an enlarged fragmentary view on a line corresponding to line 5—5 of Fig. 2.

The package of my invention illustrated comprises a stack of paper cups 1 having inset bottoms 2 and provided with bead-like rims 3 at their upper edges. These cups are shouldered at 4 adjacent their upper ends. The cups are so proportioned in their taper that they are compactly nested as illustrated. The stack of nested cups is enclosed in a wrapper 5 in the embodiment illustrated of transparent heat sealable material which is wrapped sidewise around the stack of cups, the edges of the wrapper being brought into overlapping relation as shown at 6—6 in Fig. 4 and the overlapping edges being heat sealed, preferably at least that part embracing the portion of the stack constituted by the rim portion of the receptacle. The ends 7 and 8 of the wrapper are gathered or brought together and heat sealed at 9 and 10, the bottom end of

2

the wrapper being tucked into the recessed bottom end of the bottom cup of the stack as shown in Figs. 2 and 3.

The top end 8 of the wrapper is turned or tucked into the open end of the top cup of the stack. This top end 8 is desirably of such length that when turned inwardly, it extends substantially to the bottom of the top receptacle permitting a package to be nested with other packages without rupturing thereof.

The package preferably includes a label 11 in the form of a strip or band which is disposed within the wrapper facing outwardly so as to be readable through the transparent wrapper. The ends of this label are secured with the gathered heat sealed ends of the wrapper so that the label is positioned and supported against displacement and in position for attractive display.

The receptacle of my invention is effectively protected throughout and the wrapper is secured so that the package may be quite roughly handled without danger of displacing the package. Designs or ornamentations on the receptacles are effectively displayed when wrapped of transparent material.

I have not illustrated the receptacles as bearing ornamental designs. It would be understood that only the ornamental designs of the bottom receptacles of the stack would be displayed as the others are obscured by the nesting.

Having thus described my invention, what I claim as new and desire to secure by Letters Patent is:

1. A package comprising a stack of tapered nested receptacles having inset bottoms, a wrapper of transparent heat sealable material wrapped sidewise around the stack with the longitudinal edges of the wrapper in over-lapping relation and heat sealed along at least that portion of the stack constituted by the rim portions of the receptacles, the ends of the wrapper extending substantially beyond the ends of the stack and being gathered to central points and heat sealed to close the ends of the wrapper, the bottom sealed end of the wrapper being tucked inwardly into the recessed bottom of the bottom receptacle of the stack and the top sealed end of the wrapper being turned inwardly into the top receptacle of the stack and extending substantially to the bottom thereof permitting packages being nested without rupturing the wrappers thereof.

2. A package comprising a stack of tapered nested receptacles having inset bottoms, a wrap- 55 per of heat sealable material wrapped sidewise

around the stack with the longitudinal edges of the wrapper in over-lapping relation and heat sealed along at least a portion of its length, the ends of the wrapper extending substantially beyond the ends of the stack and being gathered to central points and heat sealed to close the ends of the wrapper, the bottom sealed end of the wrapper being tucked inwardly into the recessed bottom of the bottom receptacle of the stack and the top sealed end of the wrapper being turned inwardly into the top receptacle of the stack.

3. A package comprising a stack of tapered nested receptacles having inset bottoms, a wrapper of transparent heat sealable material wrapped sidewise around the stack with the longitudinal edges of the wrapper in over-lapping relation and heat sealed along at least a portion of its length, the ends of the wrapper extending substantially beyond the ends of the stack and being gathered to central points and heat sealed to close the ends of the wrapper, the bottom end of the wrapper being tucked inwardly into the recessed bottom of the bottom receptacle of the stack and the top sealed end of the wrapper being turned inwardly into the top receptacle of the stack, there being an outwardly facing label strip disposed longitudinally within the wrapper with the ends thereof secured with said gathered heat sealed ends of the wrapper.

4. A package comprising a stack of tapered nested receptacles, a wrapper of transparent material wrapped around the stack with the longitudinal edges of the wrapper in over-lapping relation, the ends of the wrapper extending beyond the ends of the stack and being gathered to close the ends of the wrapper, the top sealed end of the wrapper being turned inwardly into the top receptacle of the stack and extending substantially to the bottom thereof permitting packages being nested without rupturing wrappers thereof, there being an outwardly facing label strip disposed longitudinally within the wrapper with the ends thereof secured with said gathered secured ends of the wrapper.

5. A package comprising a stack of tapered nested receptacles having inset bottoms, a wrapper of transparent heat sealable material wrapped around the stack with the longitudinal edges of the wrapper in over-lapping relation and heat sealed along at least a portion thereof, the ends of the wrapper extending beyond the ends of the stack and being gathered and heat sealed to close the ends of the wrapper, the sealed ends of the wrapper being disposed within the recessed bottom of the bottom receptacle of the stack and within the top receptacle of the stack, there being a label disposed facing outwardly within the wrapper and secured by said gathered heat sealed ends of the wrapper.

6. A package comprising a stack of tapered

nested receptacles having inset bottoms, a wrapper of heat sealable material wrapped around the stack with the longitudinal edges of the wrapper in over-lapping relation and heat sealed along at least a portion thereof, the ends of the wrapper extending beyond the ends of the stack and being gathered and heat sealed to close the ends of the wrapper, the sealed ends of the wrapper being disposed within the recessed bottom of the bottom receptacle of the stack and within the top receptacle of the stack.

7. A package comprising a stack of tapered nested receptacles, a wrapper of transparent heat sealable material wrapped around the stack with the longitudinal edges of the wrapper in over-lapping relation, the ends of the wrapper extending substantially beyond the ends of the stack and being gathered and heat sealed to close the ends of the wrapper, the sealed top end of the wrapper being disposed within the top receptacle of the stack, there being a label disposed facing outwardly within the wrapper and secured by said gathered heat sealed ends of the wrapper.

8. A package comprising a stack of tapered nested receptacles, a wrapper of heat sealable material wrapped around the stack with the longitudinal edges of the wrapper in over-lapping relation, the ends of the wrapper extending substantially beyond the ends of the stack and being gathered and heat sealed to close the ends of the wrapper, the sealed top end of the wrapper being disposed within the top receptacle of the stack.

9. A package comprising a stack of tapered nested receptacles having inset bottoms, a wrapper of transparent material wrapped around the stack with the longitudinal edges of the wrapper in over-lapping relation, the ends of the wrapper extending beyond the ends of the stack and being gathered and secured to close the ends of the wrapper, the closed bottom end of the wrapper being disposed within the recessed bottom of the bottom receptacle of the stack and the closed top end within the top receptacle of the stack, there being a label disposed facing outwardly within the wrapper and secured by said gathered heat sealed ends of the wrapper.

CARL T. COLGREN.
